UNITED STATES PATENT OFFICE.

GEORGE EMIL STAHL, OF JERSEY CITY, NEW JERSEY.

DESIGN FOR A COUNTER-CARBONATOR.

53,867.

Specification for Design.

Patented Sept. 16, 1919.

Application filed January 11, 1919. Serial No. 270,743. Term of patent 7 years.

To all whom it may concern:

Be it known that I, GEORGE EMIL STAHL, a citizen of the United States, and resident of Jersey City, in the county of Hudson and State of New Jersey, have invented a new, original, and ornamental Design for a Counter-Carbonator, of which the following is a specification, reference being had to the accompanying drawing, forming part thereof.

An embodiment of my new design for a counter carbonator is shown in perspective in the accompanying drawing.

I claim:

The ornamental design for a counter carbonator, substantially as shown.

GEORGE EMIL STAHL.
